AUTOMOBILE SIGNAL

Filed Dec. 1, 1922

William Smith
By *John E. Den* Attorney

UNITED STATES PATENT OFFICE.

WILLIAM SMITH, OF OLEAN, NEW YORK.

AUTOMOBILE SIGNAL.

Application filed December 1, 1922. Serial No. 604,202.

To all whom it may concern:

Be it known that I, WILLIAM SMITH, a citizen of the United States, residing at Olean, in the county of Cattaraugus and 5 State of New York, have invented certain new and useful Improvements in Automobile Signals, of which the following is a specification.

This invention relates to automobile signals, and has for its object to provide an improved signal which can be operated by the driver of the vehicle for the purpose of notifying other cars of an intended stop, turn, or similar operation.

15 The device includes a casing, and a pivoted arm which can be swung into or out of the casing by operating a lever, the arm being provided with a lamp which is lighted when the arm is swung out, by means of contacts which are automatically closed when the arm is swung out, the circuit being opened when the arm is swung in the other direction into its casing. The arm may be provided with a stop sign or other mark as 25 desired.

The invention will be more fully understood from the following description and the accompanying drawings, in which Fig. 1 is a perspective view of the device with 30 parts in section and the arm swung out. Fig. 2 is a side or edge view with the arm swung in. Fig. 3 is a detail in section showing the contact devices at the end of the arm. Fig. 4 is a cross section on the line 4-4 of 35 Fig. 2.

The device may be mounted on an automobile in any convenient way, being preferably attached to the front of the car, beside the driver's seat. For the closed car, 40 I have indicated at 6 one of the front vertical posts of the car top and to this is attached a casing, which may be made of metal, and comprises a back plate 7, a front plate 8 with curved ends joined thereto, and 45 an inner side plate 9, the outer side 10 being left open to receive the signal arm. This arm consists of an elongated metal casing with top and bottom plates 11 and 12, closed at the ends, but open at the front and rear 50 sides to disclose the illuminated tube 13 at the front or the rear or both, the tube being enclosed within the arm. The tube is made of transparent material, such as red celluloid, and is illuminated by lamps 14 one of 55 which is located at each end of the tube. Each lamp is enclosed within a socket 15,

the ends of the tube being also fitted in these sockets or shells, whereby the tube is supported. The tube may be marked with a "stop" sign or the like, and each lamp is 60 screwed in the socket for electrical connection to a current wire.

The inner end of the arm is pivoted between the front and back of the casing by a pivot pin 16, which permits the arm to be 65 swung up into the casing or swung down and out perpendicularly thereto, whereby the arm projects beyond the side of the car and can be seen from the rear.

The means for swinging the arm comprise 70 a lever 17 which is pivoted on the pin 16. This pin, in addition to extending across the casing, also extends thru the post 6, the lever being conveniently located on the inside of the post, and being connected to a 75 bolt 18 which projects from the inner end of the arm thru a slot 19 formed in the plate 7 and in the adjacent portion of the post 6. It is obvious that by pressing down on the lever it turns on the pin 16 and the arm will 80 swing up into the casing, the bolt 18 traversing the slot 19 as the lever is depressed, thereby forcing down the inner end of the arm and swinging up the outer end as described.

85 The electrical connections include a supply wire 20 which is fastened by a binding post 22 to the casing and terminates in a spring finger 23 located in the lower end of the casing and projecting in position to 90 be engaged by a curved spring finger 24, when the arm is swung down. Said finger 24 is secured to the inner end of the connecting plug 25 in the socket 15 at the inner end of the arm, and is also connected by a 95 wire 26 to a connecting plug 27 in the outer socket 15, said wire being housed within the arm, whereby both lamps are connected in circuit when the arm is swung down and out as stated, the finger 24 pressing against the finger 23, closes the circuit and lights the lamps. When the lever is pressed down, and the arm is swung up, the spring 24, carried by the arm, swings away from the finger 23, and opens the circuit, so that the 100 lamps are not lighted when the arm is swung up to inoperative position. Obviously the parts may be reversed or changed in operation, containing however the function of lighting the lamps automatically when the 105 arm is swung out and extinguishing the same when swung in.

As stated, the device may be applied to a closed car in the manner above described, but for an open car it may be attached in some other way, as by suitable clamping devices or clips for fastening the casing to one of the windshield supports, the manner of mounting the device on the car being immaterial to the main features of the invention. Various other changes may be made in the details of the device, within the scope of the following claim.

I claim:

In a signal, a signal arm comprising a metal casing with top and bottom plates

and closed ends, and open at opposite sides, 15 a socket fixed to each of the said ends and projecting inwardly between said plates, lamps in said sockets, and a tube of colored translucent material extending between said sockets and supported thereby in the casing, 20 the inner ends of the sockets projecting beyond the lamps for supporting connection with the ends of said tube.

WILLIAM SMITH.
